UNITED STATES PATENT OFFICE

2,547,827

INVALID BED

Otis A. Logan, Kansas City, Mo.

Application December 1, 1945, Serial No. 632,207

2 Claims. (Cl. 5—64)

1

This invention relates to improvements in invalid and hospital beds.

The principal object of the present invention is to provide a hospital bed with a mattress having a central cross section that is vertically adjustable and universally tiltable for adjustment relative to the body sections of the mattress.

Another object of the invention is to provide a hospital bed having a mattress with a central section that is mechanically movable to facilitate the positioning of a bed pan beneath the patient with a minimum of inconvenience to the patient.

A further object is the provision of a mattress for an invalid bed having a central transverse section that is mechanically operable for universal adjustment relative to the main body portions of the mattress.

Another object of this invention is the provision of an invalid bed having a manually operable central mattress section provided with means whereby it is operable by the patient positioned on the mattress.

Other objects are simplicity and rigidity of construction, ease and accuracy of operation, and adaptability for use with the various types of invalid beds having tilting mattress sections.

With these objects in view as well as other objects which will appear during the course of the specification, reference will be had to the drawings wherein:

Figure 1 is a side elevation of an invalid bed embodying this invention.

Fig. 2 is an end elevation of the bed.

Fig. 3 is an enlarged fragmentary sectional view taken on line III—III of Fig. 1.

Fig. 4 is an enlarged sectional view taken on line IV—IV of Fig. 1 with some of the parts shown in elevation.

Fig. 5 is a fragmentary sectional view taken on line V—V of Fig. 4 with parts shown in elevation.

Fig. 6 is a view similar to that shown in Fig. 4 with the central mattress section 36 lowered a distance below the end mattress sections.

Fig. 7 is a horizontal sectional view taken on line VII—VII of Fig. 6.

Fig. 8 is a sectional view taken on line VIII—VIII of Fig. 4.

Fig. 9 is a sectional section of lazy-tong frame and central mattress section frame showing the relative tilting of the parts.

Throughout the several views like reference characters refer to similar parts and the numeral 20 designates a bed frame having head member 22, foot member 24 and side rails 26 of

2

conventional form. Resilient elements or mattresses 28 and 30 having supporting frame 29 disposed respectively adjacent the head and foot of the bed are hinged at their inner ends at 32 and 34 to the side rails 26 for tilting lengthwise of the bed. The outer ends are provided with any of the usual means for raising and lowering, not shown. A transverse centrally disposed resilient mattress section 36 positioned between mattress sections 28 and 30 extends entirely across the bed and is carried for vertical adjustment by side rails 26 as hereinafter described.

A housing 38 comprising side walls 40 and end walls 42 which are secured to the side rails 26 extends downwardly from the side rails and serves as supports for means for raising and lowering mattress 36.

A rectangular frame 44 serving to support a rectangular frame 46 having springs 48 for supporting mattress section 36 is carried on the upper ends of lazy-tong bars 50 and 52 which are connected for free movement to frame 44 by pivotally mounted links 54 engaging with lugs 56 integral with the frame.

The lower ends of bars 50 and 52 are respectively pivotally connected with nuts 58 operatively mounted on threaded sleeves 60 and 62 which are fixed to operating shaft 64, rotatably mounted in bearings 66 fixed to end walls 42 of housing 38. The threads 68 of sleeve 60 are right-hand and the threads 70 of sleeve 62 are left-hand, so that as the shaft is rotated the nuts 58 will be moved in opposite directions to operate the lazy-tongs.

The bars 50 and 52 are pivoted intermediate their ends to a rod 72 which extends through guide slots 74 formed through side walls 40 of housing 38 whereby the lazy-tongs 50 and 52 at opposite sides of frame 44 are guided. Referring to Fig. 7 it will be noted the nuts 58 each have projecting arms 80 with end trunnions 82 for respectively receiving the ends of bars 50 and 52; furthermore, a pair of guide rods 84 supported at their ends in end walls 42 and disposed in parallel relation with shaft 64, pass through holes 86 formed through arms 80 whereby the lazy-tongs are secured against rotation about shaft 64. At both sides of housing 38 the ends of shaft 64 extend through walls 42 and are provided with fixed ratchet wheels 88 which serve as collars to preclude longitudinal movement of the shaft in the frame and also serve to facilitate ratcheting of the shaft as hereinafter described.

The lazy-tong structures just described for supporting mattress section 36 at different vertical

positions relative to the head and foot mattress sections 28 and 30 is so constructed that it will always maintain the supported mattress against accidental movement. This is apparent because the weight applied to the mattress will not transmit any force to the nuts 58 that would tend to rotate operating shaft 64. Means for operating shaft 64 are shown and include three different structures that might be used. It will be noted that operating shaft 64 is provided at each of its opposite ends with squared sections 90 which project beyond the ratchet wheels 88. The simplest means for raising and lowering the movable section of the bed is the crank 92 which may be adjusted on either of the square ends 90 of the shaft whereby to rotate operating shaft 64 manually to adjust the height of the movable section. When the crank 92 is not needed it may be removed and positioned out of the way.

A ratcheting means best shown in Figures 4 and 8 is provided so that one lying on the bed may grasp and oscillate a lever 94 to cause a ratcheting movement of the operating shaft in either direction. Lever 94 is provided with a round opening 96 for rotation on the squared end 90 of operating shaft 64 and carries a Y-shaped pawl member 98 by means of pivot 100.

Referring to Figure 8 it will be noted that the Y pawl member 98 is inverted with the upper end thereof pivoted at 101 to a rod 102 which passes through a transverse lug 104 integral with lever 94. When the pawl and rod are in the position shown in Figure 8 the engaging tooth 106 of said pawl will operatively engage the teeth of ratchet wheel 88 so that by simply oscillating lever 94 the operating shaft may be rotated in one direction. During the idle stroke of the lever the engaging point tooth will ratchet over the ratchet teeth of wheel 88 due to the force exerted by spring 108 mounted on rod 102 between lug 104 and the pivotal head of the pawl member. It is quite apparent that the operator may flip the upper end of rod 102 beyond the center whereby the engaging tooth 110 of pawl 98 will be lowered to engage the teeth of ratchet wheel 88. The operator may then be able to rotate the operating shaft 64 in the opposite direction. This ratchet mechanism may be easily removed or positioned on shaft 64.

A power means for raising and lowering the bed section comprises a motor 112 driving a belt wheel 114 which is operatively connected through belt 116 with a belt wheel 118 rigidly attached to operating shaft 64. Since it is necessary to both raise and lower the movable section it would be necessary to provide a motor of the reversible type.

Referring to the rectangular frames 44 and 46 best shown in Figures 3 and 4 it will be noted that both are made of angled iron and that the upper frame 46 normally telescopes with the lower frame 44 and rests thereon to carry the mattress 36. It is one of the principal features of this invention to provide limited universal adjustment of the mattress carrying frame 46 relative to the frame 44 which is carried by the lazy-tongs. An adjusting screw 120 is operatively mounted in a threaded nut section 122 adjacent each corner of

frame 44 with its end resting against the underside of frame 46. As the screw is turned upwardly in the nut it will raise the mattress carrying frame to tilt the mattress relative to the head and foot mattress. Any single adjusting screw 120 may be operated to tilt any particular corner of the mattress or two or more of the screws may be adjusted to obtain tilting of the mattress at various angles. While only relatively slight tiltings may be obtained by the structure shown, however, these adjustments are intended primarily to add to the comfort of the patient due to change in position or parts of the body to relieve fatigue and to stimulate circulation. For convenience of operating screws 120 it will be noted that windows 124 have been cut in the end walls 42 of housing 38.

From the above description it is quite evident that the present transverse mattress section 36 may be positioned vertically or tilted in any desired direction to conform to the foot and head mattresses 30 and 28 as they are adjusted on their hinges for the positioning of the patient. Furthermore, by the manipulation of this center mattress section, the bed pan may be easily positioned and removed without the usual discomfort to the patient.

What I claim as new and desire to protect by Letters Patent is:

1. A hospital bed having a pair of lazy-tongs operatively carried by said bed, a central transverse frame carried by said lazy-tongs for vertical adjustment, a mattress carrying spring frame carried by said transverse frame, and adjusting screws carried by said transverse frame operable to engage and tilt said spring frame relative to said transverse frame.

2. A hospital bed having a bed frame, a pair of lazy-tongs operatively carried by said bed frame, a central transverse frame carried by said lazy-tongs, a mattress carrying spring frame carried by said transverse frame, a rotatably mounted shaft carried by said bed frame operable to cause said lazy-tongs to raise and lower whereby said spring frame is vertically adjusted, and manually operable adjusting screws carried by said transverse frame and operable to tilt said spring frame relative to said transverse frame.

OTIS A. LOGAN.
